CYLINDER DOOR CONSTRUCTION

Charles E. Waream, Norwood, Ohio, assignor to
The American Laundry Machinery Company,
Norwood, Ohio, a corporation of Ohio

Application October 23, 1935, Serial No. 46,293

3 Claims. (Cl. 220—41)

This invention relates to a cylinder structure such as is found in washing and dry cleaning machines and more particularly to improvements in the construction of door closures for such cylinders.

Cylinders in machines of the type described are provided with one or more side openings and circumferentially sliding doors for said openings. Necessarily these doors are guided during their sliding movement and sufficient play is allowed between the door and the guides to permit the doors to slide easily. During rotation of the cylinder in a washing or dry cleaning operation the doors move about in the space in which they are confined resulting in wearing of the parts and unnecessary noise. It is the purpose of the present invention to provide means for holding the door in a predetermined position relative to the cylinder when it is closed.

20 My invention contemplates a novel arrangement of parts by which a door is securely held against movement relative to a cylinder, the construction being so arranged that the retaining parts are cammed into securing position by the 25 final movement of the door into closed position.

My invention also provides means for camming the door into its final closed position by the latching means which retains the door closed and the utilization of this camming action to secure another portion of the door in fixed position relative to the cylinder.

Other novel features of my invention will appear from the accompanying description and the drawing and the essential features will be summarized in the claims.

In the drawing Fig. 1 is a fragmental view of a cylinder having a circumferentially slidable door in closed position and the parts being equipped with my invention; Figs. 2 and 3 are 40 sectional views along similarly numbered lines of Fig. 1; while Fig. 4 is a fragmental view of the cylinder of Fig. 1 showing the door in partially opened position.

The drawing shows a cylinder 10 having a door 45 opening 11 at one side thereof and a circumferentially slidable door 12 for closing said opening. Guide members 13 and 14 embrace the curved ends of the door and guide the same during its circumferential movement. The bottom edge of the door in its closed position enters a channel formed by a cross bar 15 and a plate 16 which are secured together and secured to the cylinder. It will be noted that the door in closed position as seen in Fig. 3 does not engage the bottom of the

channel but is held in position by other means to be described.

Latching means is provided for holding the door closed and in the form shown this comprises latch bolts 17 and 18 located near the bottom 5 edge of the door and slidably endwise into engagement with keepers 19 and 20 on the cylinder. The bolts are biased in their latching position by springs 21 and are connected by rods 22 with a retracting handle 23 pivotally mounted on the 10 door at 24. The rods 22 enter suitable openings in a collar 25 rigid with the shank of the handle so that a movement of the handle outwardly causes a partial rotation of the collar 25 and simultaneous retraction of the bolts 17 and 18. 15 It will be noted that the coacting surfaces of the latch bolts and their keepers are wedge shape so that as the bolts enter the keepers they cam the door into its closed position. The latch bolts and the actuating handle therefor may be set in suitable recesses in the door so as to present an unobstructed outer surface on the door. It will be noted that the door 12 is spaced from the cylinder 10 and this space is enclosed on the 20 curved edges of the doors by the guides and on 25 the bottom longitudinal edge of the door by the channel construction formed by the members 15 and 16.

Along the upper longitudinal edge of the door is provided means for firmly securing the door in 30 position when closed and this means is also arranged to seal the space between the door and the cylinder along the upper edge of the door when the same is closed. The arrangement shown comprises a substantially continuous strip 35 26 secured to the cylinder 10 and substantially coextensive with the upper edge of the door between the guides. Superimposed on this strip are a plurality of contiguous strips of which three are shown, 27a, 27b and 27c. The strips 26 and 40 27 substantially close the space between the upper edge of the door 12 and the cylinder 10 (as most clearly seen in Fig. 3) when the door is closed. The strip portions 27a and 27c are secured to the cylinder. The strip portion 27b is secured to 45 the door. The contiguous faces between the inner ends of the strips 27a and 27c and the outer ends of the strip 27b are bevelled in two planes as shown at 28 and 29. One cut forms a wedge shaped opening longitudinal of the cylinder between the faces 28 and 29 on the strips 27a and 27c and the complementary faces on strip 27b are also of wedge shape so as to enter and fill the wedge shape opening between the strips 27a and 27c as the door moves into closed 50 55

position. This holds the door securely in a predetermined position longitudinal of the cylinder so that it does not move lengthwise of the cylinder into contact with the guides. The other 5 bevelling of the faces at 28 and 29 is in a direction which might more properly be termed radially of the cylinder so that the ends of the strip 27b slope downwardly and outwardly while the ends of the strips 27a and 27c also slope 10 downwardly and outwardly and as these surfaces engage upon closing of the door they hold the same in a predetermined position radially of the cylinder.

Means is provided for guiding the strip 27b into 15 suitable position between the end strips as the door approaches closed position and in the form shown the continuous strip 26 is milled away between the points 28 and 29 as best seen at 30 in Fig. 3 so that strip 26 will not interfere with 20 the strip portion 27b as the door closes. The camming action of the latching means as the bolts engage their keepers serves to apply the wedge strip 27b firmly into place between the end strips 27a and 27c.

25 The construction is such that the door 12 rides upon the strips 27a and 27c as the door is opened (see Fig. 4) and this holds the strip 27b clear of the cylinder shell so that the door slides freely in case there are any protrusions on the cylinder 30 sheets such as is caused by the embossed type of cylinder perforations.

It will be understood that the strip 27b might 35 be secured to the cylinder while the two strips 27a and 27c might be secured to the door with the wedge surfaces at the contacting ends of the two outer strips with the intermediate strip sloped in the opposite direction from that shown in the drawing. This is an obvious interchange 40 of parts.

40 The mechanism at 31 biases handle 23 to its nested position. The construction at this point is clearly shown in Patent No. 1,964,114, granted June 26, 1934, to F. A. Gerlach.

What I claim is:

45 1. In a machine of the class described and comprising a cylinder member having a side opening and a circumferentially slideable door member therefor spaced from said cylinder member and having guides on said cylinder member 50 embracing the curved edges of said door member; means for preventing movement of said door member relative to said cylinder member when said door member is closed including three

5 sealing strips aligned adjacent one of the longitudinally extending edges of said door member and coextensive therewith when said door member is closed, said strips being positioned in said space between said members, the end two of said strips being secured to said cylinder, the central strip being secured to said door, said strips having coacting inclined surfaces where said end strips engage said central strip, said surfaces diverging outwardly in a direction circumferentially of said cylinder away from said door opening, and said surfaces also diverging as they extend inwardly toward the axis of said cylinder, whereby said surfaces are adapted to sealingly engage and position said door longitudinally and 15 radially of said cylinder as said door closes.

2. In a machine of the class described and comprising a cylinder having a side opening and an arcuately bent sheet forming a circumferentially slideable door therefor, means positioned 20 along the trailing edge of the door for holding said door in a predetermined position on said cylinder and spaced therefrom, said means including interfitting wedge shape parts adapted to interengage when said door is closed, one of 25 said parts being rigid with said door and the other of said parts being rigid with said cylinder, said parts lying between said cylinder and said door, said part rigid with said cylinder being of greater thickness than said part rigid with said 30 door, and means for camming said door part radially outwardly into coacting position with said cylinder part as said door is closed.

3. Cylinder door construction comprising a cylinder having a side opening, a circumferentially slideable door for closing said opening, guide means for receiving the leading edge of said door when closed, said guide means permitting additional movement of said door in closing direction when said door is closed, coacting wedge 40 shape parts on said door and cylinder, the same parts diverging outwardly in a direction circumferentially of said cylinder away from said door opening and also diverging as they extend inwardly toward the axis of said cylinder so that 45 said parts are adapted to approach each other as said door is moved into closed position, and securing means for holding said door closed, whereby said door is held against movement longitudinally, radially and circumferentially of said 50 cylinder.

CHARLES E. WAREAM.
